UNITED STATES PATENT OFFICE

125,907

DESIGN FOR A PIN CLIP

Ben Blue, Encino, Calif.

Application January 10, 1941, Serial No. 97,968

Term of patent 3½ years

To all whom it may concern:

Be it known that I, Ben Blue, a citizen of the United States, residing at Encino, in the county of Los Angeles and State of California, have invented a new, original, and ornamental Design for Pin Clips, of which the following is a specification, reference being had to the accompanying drawing, forming part thereof.

Fig. 1 is a front perspective view of a pin clip, showing my new design.

Fig. 2 is a rear elevational view.

I claim:

The ornamental design for a pin clip, as shown.

BEN BLUE.
